CUP-SHAPED WRENCH FOR THREADED FITTINGS

Edward Rausch, Baltimore, Md.

Application January 10, 1951, Serial No. 205,354

2 Claims. (Cl. 81—65)

1

This invention comprises novel and useful improvements in a wrench and more specifically pertains to a plumber's wrench especially adapted to securely grip the exteriorly threaded surfaces of such plumber's fittings as sink strainers, cup strainers, sink, closet or urinal spuds to enable the same to be easily installed or removed from their associated equipment.

The primary object of this invention is to provide an improved wrench which may be readily applied to the externally threaded surfaces of spuds or similar plumbing fittings which are difficult to hold and maintain in place while their jamb nuts are applied or removed.

A still further object of the invention is to provide a wrench of the character set forth above which shall be of an extremely compact size to enable the same to be used in the relatively confined spaces which are available for the installation of such fittings.

A still further object of the invention is to provide an improved wrench as set forth in the foregoing objects which shall be of an extremely simple, economical and light weight construction; yet shall enable the securing of an effective grip upon the externally threaded portion of the articles manipulated by the wrench; and which will not mar or damage the externally threaded surfaces of the same.

These, together with various ancillary features and objects of the invention, which will later become apparent as the following description proceeds, are attained by the present invention, a preferred embodiment of which has been illustrated, by way of example only, in the accompanying drawings, wherein:

Figure 1 is a top plan view illustrating an embodiment of a wrench in accordance with the principles of this invention;

Figure 2 is a side elevational view of the wrench in Figure 1;

Figure 3 is a vertical longitudinal sectional view, taken substantially upon the plane indicated by the section line 3—3 of Figure 1 and illustrating the manner in which the wrench is utilized, parts being broken away;

Figure 4 is a vertical transverse sectional view taken substantially upon the plane indicated by the section line 4—4 of Figure 1 and disclosing in particular the socket contracting or clamping means of the wrench; and

Figure 5 is a vertical longitudinal sectional view taken substantially upon the plane indicated by the section line 5—5 of Figure 1.

Referring now more particularly to the ac-

companying drawings, wherein like numerals designate similar parts throughout the various views, it will be seen that the wrench embodying the principles of this invention is indicated generally by the numeral 10 and that the same consists of a relatively flat and thin handle 12 which may conveniently be formed of sheet or plate material and preferably of a flat nature, this handle terminating in a laterally enlarged or widened portion 14 which is provided with an aperture through which is secured a cup-shaped socket member 16.

As will be better apparent from Figure 5, the socket member 16 has an open upper end and at its lower side is provided with an internal flange 18 for a purpose which will be later set forth, this flange terminating in a circular opening 20. The socket member extends through the aperture in the portion 14 of the handle, so that the upper end of the socket is raised slightly above the upper surface of this handle, the socket being fixedly secured to the handle as by brazing or the like, as indicated at 22 in Figure 5.

As shown in Figure 1, the socket 16 is disposed adjacent one end of the enlarged portion 14 of the handle, and a longitudinally, substantially medially disposed slot 24 extends inwardly from the outer end of the enlarged portion 14 of the handle and through the side wall of the socket 16. This slot provides a certain degree of resiliency to the socket and handle whereby the bifurcated end portion of the handle may be squeezed together causing a contraction of the socket for a purpose which will be later apparent. The slotted portion of the wall of the socket 16 is indicated by the numeral 26 in both Figures 1 and 3.

The slot 24, as above mentioned, serves to bifurcate the enlarged portion 14 of the handle and these furcations are rolled or folded upon themselves as shown in Figures 3 and 5, to provide sleeves or tubes 28 which are aligned with each other to form axially aligned and spaced journals. The rolled ends of the extensions of the 45 furcations are brazed to the socket member 16 as at 30 and to each other to form rigid sleeve-like members. These sleeves constitute journals for rotatably receiving a clamping bolt having a shank portion 32, a perpendicularly disposed handle 34 at one end thereof, a fixedly mounted annular washer or collar 36 and an externally threaded extremity 38. As shown best in Figures 1 and 4, the clamping bolt is inserted axially into and through the sleeves 28 until the collar 36 50 abuts one end of one of the sleeves, with the

threaded extremity 38 being screw-threadedly engaged into a nut 40 which is brazed or otherwise fixedly secured to the other end of the other sleeve in a recess or socket 42 thereof.

As will be readily apparent, the annular ring 36 can be integrally formed upon the bolt 32 if desired, or can be separately applied thereto and fixedly attached as by brazing or the like.

It will now be apparent that when the bolt is rotated into the nut 40, the bifurcated ends of the handle portion 14 will be closed upon the slot 24 thereby contracting the socket member 16 and causing the same to fixedly engage the externally threaded portion 44 of a fitting 46 with which the wrench is employed. In order to protect the threaded portion 44, to seat these threads and prevent marring of the same during this contraction of the socket thereon, a frictional means may be applied to the interior surface of the socket 16. In some instances, this frictional means could comprise a deformable lining such as rubber or other suitable material, but it is preferred to form the same with an internal thread 48 complementary to the threaded portion 44.

In applying spuds, strainers and the like to sinks or other articles, a portion of which is indicated at 50 in Figure 3, it will be seen that the spud or strainer is inserted through an aperture in a wall of the article, and has its head portion 52 abutting one side of this wall while a jamb nut 54 will be screwed up upon external threads 56 upon the fitting to clamp the same to the wall. Frequently, it is very difficult to hold such spuds against rotation as the jamb nut is applied, particularly since it is necessary to grip the spud or fitting upon the externally threaded portion 44 thereof.

In applying the present tool to such a situation as disclosed in Figure 3, it will be understood that the clamping bolt 32 will be unscrewed to allow the slotted end of the portion 14 to expand and the slotted socket 16 to likewise expand, whereupon the socket may be readily applied to the externally threaded portion 44 either by screwing the same thereon, sliding the same thereover or the like. When applied, the inturned flange 18 will abut the lower end of the portion 14 and may assist in supporting the same. At the same time, the aperture 20 formed by the inturned flange 18 permits access to be had through the hollow nipple portion of the fitting if desired. With the device applied as shown in Figure 3, the clamping bolt 32 is then tightened to contract the split socket 16 and cause the same to securely and tightly embrace and engage the externally threaded portion 44, thereby preventing rotation of the same, permitting manipulation of the fitting as desired, without danger of slippage or of marring the threads thereof.

It will thus be seen that the device is ideally adapted to very expeditiously and securely handle and engage in confined and cramped quarters, portions or fittings which have heretofore been very difficult to properly engage and secure.

From the foregoing, the construction and operation of the device will be readily understood and further explanation is believed to be unnecessary.

However, since numerous modifications and changes will readily occur to those skilled in the art, it is not desired to limit the invention to the exact construction shown and described, and accordingly all suitable modifications and equivalents may be resorted to, falling within the scope of the appended claims.

Having described the invention, what is claimed as new is:

1. A wrench comprising a cup-shaped unitary socket for receiving the externally threaded portion of a pipe fitting, means in said socket for receiving, protecting and frictionally engaging the external threads of said portion, means for contracting said socket upon said portion, including a handle carrying said socket, said socket and handle being slotted to permit contraction of the socket, said handle having aligned smooth bore journal sleeves on opposite sides of the slot, said contracting means comprising a bolt journaled in said sleeves, said bolt having a fixed collar engaging the outer end of one of said sleeves, a nut engaging said bolt and fixedly secured to the other sleeve.

2. A wrench comprising a cup-shaped unitary socket for receiving the externally threaded portion of a pipe fitting, means in said socket for receiving, protecting and frictionally engaging the external threads of said portion, means for contracting said socket upon said portion, including a handle carrying said socket, said socket and handle being slotted to permit contraction of the socket, said handle having aligned smooth bore journal sleeves on opposite sides of the slot, said contracting means comprising a bolt journaled in said sleeves, said sleeves consisting of integral extensions of said handle folded upon themselves, the ends of said extensions being homogeneously united to form closed tubes.
